[57] CLAIM

The excavator cab with extended rear housing, as shown and described.

DESCRIPTION

FIG. 1 is a rear perspective view of an excavator cab with extended rear housing showing a first embodiment of our new design, the broken line showing of the vehicle and tool being for illustrative purposes only, and forming no part of the claimed design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a rear perspective view of an excavator cab with extended rear housing showing a second embodiment of our new design, the broken line showing of the vehicle and tool being for illustrative purposes only, and forming no part of the claimed design;

FIG. 9 is a top plan view thereof;

FIG. 10 is a front elevational view thereof;

FIG. 11 is a right side elevational view thereof;

FIG. 12 is a left side elevational view thereof;

FIG. 13 is a rear elevational view thereof; and,

FIG. 14 is a bottom plan view thereof.
